(57) **CLAIM**

The ornamental design for a strut nut assembly as shown and described.

DESCRIPTION

FIG. 1 is an isometric view of a strut nut assembly showing our new design;

FIG. 2 is a first side view thereof;

FIG. 3 is a second side view thereof;

FIG. 4 is a first end view thereof; and

FIG. 5 is a second end view thereof

FIG. 6 is a top view thereof;

FIG. 7 is a bottom view thereof;

FIG. 8 is an isometric view of the strut nut assembly showing our new design;

FIG. 9 is a first side view thereof;

FIG. 10 is a second side view thereof;

FIG. 11 is a first end view thereof; and

FIG. 12 is a second end view thereof

FIG. 13 is a top view thereof; and,

FIG. 14 is a bottom view thereof.

The broken lines in the drawings depict portions of the strut nut assembly that form no part of the claimed design.

1 Claim, 14 Drawing Sheets
